UNITED STATES PATENT OFFICE.

HITASU NAKAI, OF HAVRE, MONTANA.

TELEPHONE TRANSMITTER AND MOUTHPIECE.

1,225,672.

Specification of Letters Patent.

Patented May 8, 1917.

Application filed June 28, 1916. Serial No. 106,344.

To all whom it may concern:

Be it known that I, HITASU NAKAI, a subject of the Emperor of Japan, and a resident of Havre, in the county of Hill and State of Montana, have invented certain new and useful Improvements in Telephone Transmitters and Mouthpieces, of which the following is a specification.

My invention relates to the provision of sanitary mouthpieces for telephone transmitters, and one of the main objects thereof is to supplant the conventional mouthpiece by an inexpensive, destructible, mouthpiece for each user of a telephone, in other words, to compel the use of the sanitary mouthpiece on the part of careless telephone users who would otherwise use any mouthpiece which might be on the telephone.

In the practice of my invention I remove the conventional mouthpiece and substitute a casing therefor serving as a holder for my sanitary mouthpieces, said holder having a rotatable perforated plate therein arranged above a permanent perforated plate with the perforations normally out of register but adapted to be brought into register upon the installation of one of my mouthpieces, thereby preventing the use of the telephone when no mouthpiece of my special construction is in place.

My invention is fully described in the following specification, of which the accompanying drawings form a part, in which like characters refer to like parts in each of the views, and in which:—

Figure 1 is a central section taken through my invention, ready for use, with its position indicated by the dotted telephone transmitter;

Fig. 2 is a detached view of the mouthpiece;

Fig. 3 is a section taken on the line 3—3 of Fig. 1;

Fig. 4 is a similar section but with the parts in the telephone using position, whereas Fig. 3 is with the parts in mouthpiece installing position;

Fig. 5 is a section taken on the line 5—5 of Fig. 1, with the parts in mouthpiece installing position;

Fig. 6 is an enlarged view of one of a plurality of nested detachable and destructible inserts which may be used in one of my mouthpieces, as for family or semi-public use where the danger of contagion may not be great or where the users will remember

to remove an insert before or after use; and Fig. 7 is a central section taken through a nest of inserts arranged within one of my mouthpieces.

Referring to Figs. 1 to 5, inclusive, 8 represents a telephone transmitter having the usual screw threaded central opening for the reception of the threaded end of a conventional mouthpiece. At 9 I have shown a threaded neck of a casing 10 engaged in this threaded opening, said casing having a perforated plate 11 in the bottom thereof, a similarly perforated disk 12 pivoted at 13, and an inwardly directed flange 14 cut away at diametrically opposite points, as shown at 15, Figs. 3 and 4, and said disk 12 is provided with extensions 16 provided with side flanges forming pockets adapted to be brought into register with the cuts 15. In this position of the disk 12 the perforations therethrough are out of register with the perforations in the plate 11, as shown in Fig. 3, a stop 17 insuring the register of the extensions 16 and cuts 15, and I provide another stop 18 for the rotary movement of the disk 12 in such position as to insure register of the perforations in the plate 11 and disk 12, as shown in Figs. 4 and 5.

Adapted for connection with the casing 10 is a bell-shaped mouthpiece 19 provided with a perforated bottom 20 and with hooks 21 adapted to be passed through the cuts 15 in the flange 14 and to be seated in the pockets of the extensions 16 whereby, when said mouthpiece is rotated to the right, the hooks 21 pass beneath the said flange to lock the mouthpiece in place and the disk 12 is rotated to impinge on the stop 18 to bring the perforations of the disk and of the plate 11 into register.

The mouthpiece 19 is composed of pure paper stock of sufficient rigidity to maintain its shape and to support the hooks 21, and I may, if desired, provide a thin sheet 22 above the perforated bottom 20 of the mouthpiece and puncture the same to defeat its functioning as a diaphragm.

It is the intent to provide a new mouthpiece for each user of the telephone and who, when he is through with the latter, will detach and destroy the mouthpiece when the telephone is in a public place, whereby it will be obligatory upon a future user of the telephone to procure a new mouthpiece, these either being in a suitable container con-

venient to the telephone or being provided by the person in charge of the telephone.

In conjunction with the mouthpiece shown I may, as in homes, offices, or semi-public places, provide a plurality of nested linings 5 or inserts 23 provided with perforated bottoms and held together in any suitable way, as by a looped wire 24, each of these having a tab 25 thereon whereby they may be successively removed after successive telephone uses, these inserts being made of very thin paper and I prefer to wax or otherwise treat the paper in any form of the mouthpiece.

15 From the foregoing it will be noted that the casing 10 interposed between the transmitter and the mouthpiece is of great importance, particularly in public places, inasmuch as it enables a telephone user to detach and destroy the mouthpiece he had used and thus compel the procuring of a new one by a subsequent telephone user.

While I have shown a preferred embodiment of the invention, it will be understood that I do not limit myself to any specific structural details as many modifications thereof will suggest themselves and still be within the spirit of the invention and within the scope of the following claims.

30 Having fully described my invention, what I claim as new, and desire to secure by Letters Patent, is:—

1. The combination with a telephone transmitter provided with a threaded opening for a mouthpiece, of a casing provided with a threaded neck engaged in said opening, a mouthpiece in detachable engagement with said casing, and means for preventing the use of said telephone operable by the removal of said detachable mouthpiece.

2. The combination with a telephone transmitter provided with a threaded opening for a mouthpiece, of a casing provided with a threaded neck engaged in said open-

ing, a mouthpiece in detachable engagement 45 with said casing, a perforated plate in the bottom of said casing, a disk rotatable in said casing provided with complementary perforations, and means on said detachable mouthpiece in engagement with said disk 50 for rotating the latter upon mouthpiece removal to carry the perforations of said disk and plate out of register.

3. The combination with a telephone transmitter provided with a threaded opening 55 for a mouthpiece, of a casing provided with a threaded neck engaged in said opening, a perforated plate in said casing, a similarly perforated disk rotatable in said casing, said casing having a flange at its 60 outer side cut away at opposed points, a mouthpiece provided with hooks adapted to be passed beneath said flange through said cuts, and means on said disk for engagement with said hooks whereby said disk is rotated 65 by said mouthpiece to carry said perforations into and out of register in the installation and removal of said detachable mouthpiece.

4. As an article of manufacture, for use 70 with a telephone provided with a casing having an interrupted flange at the front thereof; a mouthpiece provided with hooks adapted to be passed beneath said flange, a plurality of destructible mouthpieces 75 nested within said first named mouthpiece and adapted for individual removal after successive uses of said telephone, all of said mouthpieces having perforated bottoms with the perforations in register, to 80 permit the passage of sound waves, and means passed through certain perforations in all of said mouthpieces for holding the latter together while permitting the removal of the innermost one by its destruction 85 after use.

HITASU NAKAI.
